HYDRAULIC ACTUATING MECHANISM FOR
PLANERS

Donald H. West, Marlboro, and Kenneth C. Monroe, Hudson, Mass., assignors to The Lapointe Machine Tool Company, Hudson, Mass., a corporation of Maine

Application September 28, 1931, Serial No. 565,420

6 Claims. (Cl. 60—52)

This invention relates to mechanism for actuating the reciprocating table or carriage of a planer or other machine tool. The use of high speed tools in such machines renders much higher table speeds desirable, in order to fully utilize the advantages of the improved tools.

It is the general object of our invention to provide improved table-operating mechanism so designed that increased table speed is available and that smooth and rapid reversal may be accomplished.

A further object is to provide actuating mechanism which may be conveniently adjusted to vary the speed of the cutting stroke, the return speed and the rates of deceleration and acceleration at the reversal of each stroke.

We also provide mechanism by which the permissible ratio of deceleration and acceleration are much increased, which result is facilitated by eliminating the reversal of heavy rotating parts.

Our invention further relates to arrangements and combinations of parts which will be herein-after described and more particularly pointed out in the appended claims.

A preferred form of the invention is shown in the drawings, in which

Fig. 1 is a side elevation of a planer embodying our improvements;

Fig. 2 is a diagrammatic plan view showing the hydraulic actuating mechanism and connections, together with the control devices therefor, and

Figs. 3, 4, 5 and 6 are similar diagrammatic views illustrating different operating conditions.

Referring to Fig. 1, we have shown a planer having a base 10 on which a table T is guided for longitudinal sliding movement. A cylinder 13 is mounted in fixed position in the base 10 and a piston 14 is slideable in the cylinder 13 and is connected by a piston rod 15 to the right hand end of the table T, as shown in Fig. 2.

When oil or other liquid under pressure is admitted to the cylinder space 16, the table T is moved to the right for an operative movement, carrying the work under a suitable tool K.

When liquid is admitted to the annular cylinder space 17 surrounding the piston rod 15, the table T is moved to the left at relatively high speed.

Our improved planer is equipped with a suitable driving motor M which continuously rotates a relatively large table-operating pump P and a relatively small control or pilot pump P'. The planer is also provided with an automatic reversing valve mechanism V, a speed control and main differential valve mechanism V', a control

mechanism V² for the pump P, and hydraulic tool feed mechanism D. The automatic reversing valve mechanism V may be operated as usual by dogs 20 mounted on the table T and engaging an offset arm 21 on the piston rod 22 of the reversing valve mechanism V.

General operation

The general operation of our improved actuating mechanism may be briefly described as follows:

The large pump P is at all times connected to the two ends of the table-operating cylinder 13. The pump P is preferably of the rotary piston, variable discharge, reversible type shown in the prior patent to West, No. 1,722,832. The direction and rate of flow of oil to the cylinder 13 is controlled by reversing the discharge of the pump P, the connections between the pump and the cylinder remaining unchanged during operation of the planer.

The auxiliary or pilot pump P' is preferably of the same general type as the pump P, but is arranged to automatically maintain constant pressure in its discharge pipe and the discharge is never reversed, although it may be brought to zero after the predetermined pressure has been attained and in case there is no demand on the pump.

The reversing valve mechanism V changes the connections to the pump control mechanism V², and the mechanism V² operates to reverse the direction of flow of the pump P. The speed control and main differential valve mechanism V' may be set manually for either fast or slow speed operation of the cylinder on the cutting stroke, but without affecting the speed of the return stroke.

Provision is also made for automatically raising the tool from the work on the return stroke and for feeding the tool after each cut. The tool feeding mechanism D may be adjusted manually to feed at the beginning of the return stroke or at the beginning of the cutting stroke, as may be preferred, and may be adjusted to vary the rate of feed.

The connections and operation of the pump control mechanism V² are very important, as they determine the rate of movement of the reversing mechanism for the pump P and thus determine the rate of deceleration and acceleration of the table T. Furthermore, these connections may be independently adjusted to increase or decrease the rate of either deceleration or ac-

celeration, also to adjust and control the uniform rate of travel.

By this combination of mechanisms, an extremely flexible actuating mechanism is provided, by use of which a great variety of desired results may be attained.

Pump mechanism

As previously stated, the pumps P and P' are preferably of the type shown in the West Patent #1,722,832 and may be briefly described as follows:

The pump P comprises a casing 30 (Fig. 2) having plurality of pistons 31 slidable in a rotating cylinder block 32 and connected to a plate 33, rotatably mounted in a tilting holder or cradle 34.

The cradle 34 is provided with segment gear teeth 35 engaged by a pinion 36 mounted on a shaft 37 having bearings in the upper part of the casing 30 and engaged by a rack bar 38 mounted on a rod 39 which is slidable in a bearing 40 and is connected to a piston 41 and cylinder 42 forming part of the control valve mechanism V².

When the piston 41 is at one end of its path of travel, as shown in Fig. 2, the pump P will operate to discharge oil into an upper discharge pipe 44, and when the piston 41 is at its opposite limit of travel, as shown in Fig. 3, the pump P discharges oil from a lower discharge pipe 45.

The piston 41 has only three operative positions, shown in Figs. 2, 3 and 6 respectively, and these positions represent cutting, return and neutral operating conditions.

The pipe 44 is connected to the left hand end of the cylinder 13, as shown in Fig. 2, and is provided with a check valve 47 opening toward the cylinder 13. The pipe 44 is also preferably provided with a by-pass 48 having an adjustable shut-off valve 49 by which the rate of discharge from the cylinder space 16 may be controlled, so that a sufficient back pressure may be provided on the return stroke to insure smooth working of the table.

A pipe 50 connects the pipe 44 to the speed control valve mechanism V' to which the lower pump connection 45 is also attached. A branch connection 51 between the pipes 44 and 45 is normally closed by a shut-off valve 52.

The right hand end of the cylinder 13 is connected by a pipe 54 to the speed control valve mechanism V' and is provided with a check valve 55, by-pass 56 and adjustable shut-off valve 57, all as previously described in relation to the pipe 44.

When the mechanism is set for a slow speed cutting stroke, as shown in Fig. 2, oil is delivered from the pump P through the pipe 44 and past the check valve 47 to the cylinder space 16 in the cylinder 13, while the annular space 17 in the cylinder 13 is connected through the pipe 54 and by-pass 56 to the speed control valve mechanism V'.

On the return stroke, the parts take the position indicated in Fig. 3, and the flow of oil is reversed, entering the annular cylinder space 17 and being discharged from the cylinder space 16.

Reversing valve mechanism

The reversing valve mechanism V comprises a casing 60 having a cylindrical opening 61 in which pistons 62, 63 and 64 are slidable, these

pistons being mounted in spaced relation on the rod 22 previously described.

The pilot pump P' delivers oil at constant pressure through a discharge pipe 66 (Fig. 2) to a port 67 in the casing of the cylinder 61. A discharge port 68 in the cylinder 61 is connected by a discharge pipe 69 to an over-flow or storage tank S. The discharge pipe 69 may be provided with a gauge 70 and strainer 71.

Ports 72 and 73 in the cylinder 61 are connected together by a branch pipe 74 and are connected to one end of the cylinder 42 of the pump control mechanism V² by a pipe 75 having an adjustable needle valve 76 mounted therein.

Additional ports 80 and 81 in the cylinder 61 are connected by branch pipes 82 and 180 and these branch pipes are connected by a pipe 83 to the opposite end of the cylinder 42. The pipe 83 is similarly provided with an adjusting or needle valve 84.

Ports 86 and 87 in the cylinder 61 are connected by additional pipes 88 and 89 to intermediate ports in the side of the cylinder 42. A pipe 90 branches off of the pipe 88 and leads to one end of the upper cylinder in the speed control and main differential valve mechanism V', while a pipe 91 branches off of the pipe 89 and leads to the opposite end of the same upper cylinder in the valve mechanism V'.

Additional branch pipes 92 and 93 lead off of the pipes 88 and 89 and are provided with adjusting or needle valves 94 and 95. The pipes 92 and 93 are joined to a common pipe 96 which connects to an opening at the lower side of the casing 30 of the pump P. A corresponding opening at the upper side of the casing is connected by a pipe 97 to a pipe 98, which in turn is connected to the discharge or surge pipe 99 of the storage tank S.

Pilot pump and control connections

The pipe 98 has an additional connection 100 to the tank S and also has a connection 101 to the under side of the casing of the pilot pump P'. An additional connection 102 leads to the left hand end of the control cylinder 103 for the constant pressure or pilot pump P'. The opposite end of the cylinder 103 is connected by a pipe 104 to the discharge pipe 66 of the pump P'.

A pipe 105 leads from the casing to the intake of the pump P', so that the oil supply of the pump P' is drawn from the tank S through the branch pipe 100, pipe 98 and branch pipe 101. The latter pipe delivers the oil to the lower part of the casing of the pump P' through which casing the oil flows to the pipe 105, by which the oil is delivered to the intake of the pump P'. The discharge of the pump P' is delivered through the pipe 66 to the reversing valve mechanism V.

A piston 110 is slidable in the cylinder 103 and is connected by a rod 111 to a rack 112, engaging a pinion 113 adapted to rock the output control cradle 114 of the pilot pump P'.

A spring 115 acts against a collar 116 on the rod 111 to move the piston 110 to the right in Fig. 2, or in a direction to increase the discharge of the pump P'. A portion of the oil discharged from the pump P' is delivered through the pipes 66 and 104 to the cylinder 103 and tends to move the piston 110 to the left or in a direction to decrease the discharge of the pump.

By suitably selecting or adjusting the spring 115, the pressure of the oil against the piston 110 will balance the pressure of the spring 115 at a predetermined discharge pressure and this

predetermined pressure will be continuously maintained by the pump P'. If oil is discharged through the pipe 66 in sufficient quantity to cause a drop in pressure, the spring 115 will overcome the pressure on the piston 110 and will move the rack 112 in a direction to increase the discharge of the pump, thus bringing the pressure back to the predetermined normal.

10 *Speed control and main differential valve mechanism*

The speed control and main differential valve mechanism V' comprises a casing 120 having an upper cylinder 121 and a lower cylinder 122. 15 Three pistons 123, 124 and 125 are mounted in spaced relation on a piston rod 126 in the upper cylinder 121, and two pistons 127 and 128 are similarly mounted in spaced relation on a piston rod 129 slidable in bearings at the ends of the lower cylinder 122 and connected for manual 20 operation by a hand lever 130 (Fig. 1).

The rod 129 is also provided with a slightly enlarged portion providing a shoulder 131 which limits movement of the rod and pistons to the left in Fig. 2.

25 The pipe 54 connects the space 17 (Fig. 2) of the cylinder 13 to a port 133 which opens into both the upper and lower cylinders 121 and 122. Similarly, the pipe 45 connects with a port 134, 30 also opening into both cylinders, and a pipe 136 is connected at one end through the pipe 99 to the storage tank S and at its lower end through branch connections 137 and 138 to ports in the upper cylinder 121.

35 The branch pipe 50 previously described also connects the upper pump discharge pipe 44 to an additional port in the upper cylinder 121.

When the rod 129 and pistons 127 and 128 are in the position shown in Fig. 2, the piston 14 and table T will be moved at relatively slow speed, 40 as the discharge of the pump P will be delivered through the pipe 44 to the cylinder space 16, while the annular space 17 at the opposite end of the cylinder will be connected through the pipe 54, ports 133 and 134 and pipe 45 to the intake of the pump P.

45 As the oil forced out of the cylinder space 17 is much less in amount than the oil forced into the cylinder space 16, additional oil is supplied to the pump P from the storage tank S through the pipes 99 and 136, branch pipe 138 and pipe 45. The piston 14 is thus moved at the rate at which the full discharge of the pump will fill the cylinder space 16.

50 For high speed operation, (Fig. 4) the handle 130 is shifted to move the valve rod 129 and pistons 127 and 128 to their left hand limit of travel, thus connecting the pipe 54 through the ports 133 and 135 to the upper cylinder 121 and thence through the branch pipe 50 to the discharge pipe 44 of the main pump P.

55 In this case, the oil discharged from the annular cylinder space 17 is by-passed around to the cylinder space 16 and it is only necessary for the pump P to supply oil equivalent to the difference in volume between the space 17 and the space 16. Consequently a given amount of oil delivered by the pump to the space 16, being used in addition to that by-passed around the piston 14, will produce substantially more rapid travel of the piston 14 and table T than when the oil is not by-passed.

60 During a high speed cutting stroke, no part of the oil discharged from the cylinder space 17 will return to the pump P and the oil supply of

the pump must be obtained through the pipes 99 and 136, branch pipe 138, upper cylinder 121 and pipe 45.

65 *Return stroke*

The position of the differential valve in the upper cylinder 121 of the valve mechanism V' is determined by the application of pressure at the ends of the valve through the pipes 98 and 91 previously described.

70 During the operative stroke, pressure will be applied through the pipe 91, as indicated in Fig. 2, maintaining the upper piston valve in its right hand position, but on the return stroke pressure will be applied through the pipe 98, as indicated in Fig. 3, forcing the upper piston valve to the left.

75 This movement of the upper or differential valve is timed to take place when the piston 41 of the reversing valve mechanism V² is just passing neutral or mid-position, at which time the pump discharge is substantially zero. The rack 38 and gear 36 are in such mechanical relation to the piston 41 that when the piston is in mid-position, the cradle 34 is in neutral or no-discharge 80 position as shown in Fig. 6. As soon as the piston 41 moves beyond mid-position in either direction, one of the pipes 88 or 89 is uncovered and the valve in the upper cylinder 121 is shifted before substantial movement of the cradle 34 85 from neutral position can occur. This is an extremely important feature of our invention, as serious results might be obtained if the differential valve was shifted while the pump was discharging in either direction.

90 The parts are shown in Fig. 3 as positioned for the return stroke after a high speed cutting stroke. Under these conditions, the pump P discharges through the pipe 45, upper part of port 134, port 133 and the pipe 54 to the right hand end of the cylinder 13, while the left hand end of the cylinder is directly connected through the pipe 44 to the intake of the pump P.

95 As the volume discharged from the cylinder 13 through the pipe 44 is greater than the volume supplied to the cylinder through the pipe 54, the surplus oil is delivered through the branch pipe 50, upper cylinder 121 to the branch pipe 137, and thence through the pipes 136 and 99 to the storage tank S.

100 The opposite ends of the lower cylinder 122 are connected through passages 140 to ports in the upper cylinder which are connected through the branch pipes 137 and 138 to the storage tank. This permits out-flow of oil at the ends of the cylinder as the lower piston valve is shifted.

105 The operation of the valve mechanism for a return after a slow speed stroke is not shown in the drawings but is substantially identical with the operation after a high speed stroke, the only difference being that the path of flow of liquid from the pipe 45 to the pipe 54 is directly through the upper and lower parts of the port 134, instead of through the ports 134 and 133 successively as previously described. No difference in ultimate result is produced.

110 *Tool feeding mechanism*

115 We have provided means for feeding the tool at either end of the path of travel, as may be desired. For this purpose we provide a cylinder 142 (Fig. 2) in which a piston 143 is slidable. The piston 143 is mounted on a piston rod 144, the upper end of which is threaded and is provided 120

- with adjustable stops 145 and 146, engaging opposite sides of a fixed abutment 147. At its lower end, the piston rod 144 may be connected in any convenient manner to operate 5 the cross feed of the cutting tool.
- In Fig. 2 we have indicated these connections as comprising a ratchet wheel 148 mounted on a cross feed shaft 149 and engaged by a double pawl 150 mounted on the lower end of the valve rod 144. The pawl 150 may be set to operatively engage the ratchet 148 either on the upward stroke or on the downward stroke, as may be desired, and may be provided with any suitable 10 spring devices for holding it in yielding engagement with the ratchet in either position.
- A pipe 152 connects the lower end of the cylinder 142 to a control cylinder 154 at about the middle of its length. The upper end of the cylinder 142 is connected by a branch pipe 156 15 to the upper end of the cylinder 154, and by a branch pipe 158 to a lower point in the cylinder 154.
- Pistons 157, 158 and 159 are mounted in spaced relation on a piston rod 160 extending upward 20 through the cylinder 154 and manually adjustable to high, low or intermediate positions.
- A pipe 162 is connected at one end to the discharge pipe 44 of the pump P and at the other end to a port in the side of the cylinder 154 25 between the ports for the pipes 152 and 155. A pipe 163 is similarly connected at one end to the discharge pipe 45 of the pump P and at the other end to a port in the cylinder 154 between the ports for the pipes 152 and 158.
- The cross feeding mechanism is shown in Fig. 2 30 in the position for feeding just prior to the beginning of the cutting stroke. The valve rod 160 is in its raised position, and oil under pressure is delivered from the pump discharge pipe 44 through pipe 162, control cylinder 154, and pipe 152 to the lower end of the cylinder 142, giving the piston 143 an upward feeding stroke as the pressure is built up in the discharge pipe 44 as the pump P is reversed and just prior to the working stroke.
- When the pump P is again reversed at the end 35 of the cutting stroke, pressure in the pipe 45 will be transmitted through the pipe 163, cylinder 154, and pipes 156 and 155 to the upper end of the cylinder 142, thus forcing the piston 143 downward and giving the pawl 150 an idle or return movement. The amount of feed may be controlled by the setting of the stop nuts 145 and 146.
- If the valve rod 160 is moved to its middle or 40 neutral position, the pistons 157 and 158 close the port openings of the pipes 162 and 163, and the cross feed is thus rendered inoperative.
- If the valve rod 160 is moved to its lowest position, oil under pressure will be delivered from 45 the pipe 162 through the pipe 155 to the upper end of the cylinder 142 to effect an idle return movement just prior to the beginning of the cutting stroke, and will be delivered from the pipe 163 through the pipe 152 to the lower end of the cylinder 142 to effect a feeding movement just 50 prior to the beginning of the return stroke. Consequently, feed will take place at the beginning of the return stroke rather than at the beginning of the cutting stroke.
- By reversing the setting of the pawl 150, cross feed in the opposite direction may be attained.

Tool lifting device

- 75 It is desirable under some conditions that the

cutting tool K be lifted from the work during the return stroke, so that the edge of the tool will not be dulled or broken by being dragged over the surface of the work. For this purpose we provide a small cylinder 170 (Fig. 2) mounted in the tool holder or clapper 171 and having a piston 172 mounted on a plunger 173 which projects through the outer end of the cylinder 170 and engages the cross head 174.

A pipe 175 connects the cylinder 170 to the 10 pipe 163 which in turn is connected to the pipe 45 to which oil is delivered under pressure during the return movement of the table.

Consequently, whenever pressure is applied in the pipes 45 and 163, pressure will also be applied through the pipe 175 to the cylinder 170, forcing the piston 172 into the cylinder against the pressure of a spring 176.

As the cross head 174 cannot yield, the tool holder or clapper 171 is thereby swung outward, 20 raising tool K away from the table T during the return stroke.

A control valve 176 provides for adjustment of the rate of movement of the tool holder 171 and a by-pass 177 with a check valve 178 permits quick seating of the tool holder before the cutting stroke.

Operation

Having described the details of construction of our improved mechanism, the method of operation is as follows:

The mechanism is first set for a fast or slow speed cutting stroke by manual adjustment of the handle 130, by which the speed control valve in the lower cylinder 122 of the valve mechanism V is adjusted. The feed control valve rod 160 is also set to effect the intermittent feed just prior to the return stroke or just prior to the cutting stroke, as may be desired under existing operating conditions.

Disregarding for the present the devices by which deceleration and acceleration are controlled, we will assume that the reversing valve V is in the position shown at Fig. 2, with the table T moving to the right. It will be seen that oil at constant pressure will be delivered by the pilot pump P' through the pipes 66 to the reversing valve cylinder 61 and thence through the pipes 74 and 75 to the right hand end of the control cylinder 42, forcing the piston 41 to its left hand limit of travel and adjusting the main pump P for maximum predetermined discharge through the pipe 44.

This effects a working stroke of the table T at high or low speed, in accordance with the setting of the valve rod 129 by handle 130. At the same time, the pipe 83 from the left hand end of the control cylinder 42 is connected through the cylinder 61 and pipe 69 to the storage tank S. At the end of the cutting stroke, the reversing valve V is shifted to the position shown in Fig. 3, so that oil under pressure is delivered from the pilot pump P' through the pipe 66, cylinder 61 and pipe 83 to the left hand end of the control cylinder 42.

This moves the piston 41 to the right and reverses the discharge of the pump P, so that the pump now discharges through the pipe 45 to the right hand end of the cylinder 13, causing a return movement of the piston 14 and table T. At the same time, the pipe 75 from the right hand end of the cylinder 42 is connected through the cylinder 61 and pipe 69 to the storage tank S.

It will be noted that whenever oil is delivered to either end of the cylinder 13 by the pump P,

this oil flows freely past the check valve 47 or 55, but that when oil flows from the cylinder 13 to the pump P, this flow is resisted by the check valves and must take place through the by-pass 5 48 or 56, such flow being regulated by the adjusting valves 49 and 57. Consequently, any desired back pressure can be maintained on the piston 14, so as to induce a smooth and even motion in either direction.

10 *Operation of pump control mechanism V²*

A very important part of our invention relates to the operation of the mechanism V², which effects the reversal of the pump P and consequently the deceleration and acceleration of the table T.

During the cutting stroke, the piston 41 of the control mechanism V² is in the left hand position shown in Fig. 2, and the reversing valve mechanism V is also in the position shown in Fig. 2.

At the end of the cutting stroke, the arm 21 is engaged by one of the dogs 20 and the reversing valve is moved to the right toward the 25 position shown in Fig. 3. As the reversing valve starts to move, oil under pressure is first admitted through the branch pipe 180 and pipe 83 to the left hand end of the cylinder 42.

As the port for the pipe 88 in the cylinder 42 30 is closed by the piston 41, the full oil pressure is applied to the left hand side of the piston 41 but the rate of flow to the cylinder 42 is controlled by the setting of the regulating valve 84.

The right hand end of the cylinder 42 is still 35 connected to the oil supply through the pipe 15 and branch pipe 74, but the port to the pipe 89 is open so that oil can flow past the regulating valve 95 to the pipe 93 and thence through the casing of the pump P to the storage tank S. 40 Consequently the oil pressure in the right hand end of the cylinder 42 is somewhat reduced and the piston 41 begins to move toward the right, the rate of movement being controlled by the setting of the valves 84, 76 and 95.

45 Pressure is maintained in the pipe 91 and the piston valve in the upper cylinder 121 of the valve mechanism V' remains in the position shown in Fig. 2, with the pipe 90 connected to the return.

50 Meanwhile, the reversing valve continues its travel to the right until the port 87 for the pipe 88 is uncovered, thus connecting the pipes 89 and 90 to the return pipe 69, which connects directly to the storage tank S and allows the oil to return 55 without passing through the regulating valve 95.

In the meantime, the piston 41 has been moving 60 toward the right. During the first part of its stroke this movement was due to the net difference in pressures on the two sides of the piston 41 and was controlled by the three valves 84, 95 and 76.

65 By the time the pipe 89 was connected to the return pipe 69, the piston 41 had been moved far enough to shut off the connection to the pipe 89 from the cylinder 42.

The pressure in the pipe 91 and the left hand 70 end of the cylinder 121 was thus relieved, and a slight dwell of the reversing mechanism of the pump P occurs, as there is balanced pressure on the piston 41.

A slight continued movement of the reversing 75 valve causes the piston 62 to shut off the oil supply to the branch pipe 74 and a slight further movement brings the valve to the final position

with the pipe 75 connected to the return pipe 69, as shown in Fig. 3.

During the continued movement of the piston 41 to the right, the oil ejected from the cylinder 42 is all forced to escape through the pipe 75 and is controlled by the valve 76.

Furthermore during the latter part of the stroke of the piston 41, the connection from the left hand end of the cylinder to the pipe 88 is opened, thus reducing the effective pressure to move the piston 41, as a portion of the oil under pressure escapes past the valve 94 and through the pipe 92 to the casing of the pump P and thence to the storage tank.

When the pipe 88 is uncovered, oil under pressure acts through the pipe 90 to move the piston valve in the cylinder 121 to the left, reversing the connections to between the pump P and the cylinder 13. This reverse movement of the valve in the cylinder 121 takes place when the pump 20 P is in neutral position and there is no discharge from the pump through either outlet. The cross feed and tool lifting devices operate at relatively low pressure and complete their movements before the pressure is built up to a point 25 sufficient to move the table.

The result of these several valve movements is to bring the pump P back to neutral position at a relatively more rapid rate of movement and to move the pump P from neutral to reverse position at a relatively slower rate, as it has been found that a heavy planer table or similar object can be decelerated or brought to rest more quickly than it can be accelerated or brought up to speed in the opposite direction.

30 The branch pipes 92 and 93 and the regulating valves 94 and 95, taken in connection with the adjusting valves 76 and 84, permit us to vary the rate of movement of the piston 41 during different parts of its travel and to cause the pump 40 P to be brought to neutral and to be rendered operative in the reverse direction in any desired time intervals.

35 Suitable provision is made for determining the setting of the pump P for discharge in each direction. In Fig. 2 we have indicated adjustable stop screws 181 and 182 positioned for engagement by a lug or projection 183 on the rack 38. By adjusting the screws 181 or 182, the limit of movement of the rack in each direction may be 45 determined, which in turn will determine the extreme positions of the rocking cradle 33 and will thus determine the rates of discharge of the pump P.

40 It will be evident that this rate of discharge 55 may be independently adjusted for each direction of operation, so that the speed of the table T during its working stroke and also during its return stroke may be independently determined. Under ordinary conditions, the return stroke will 60 be made at substantially higher speed than the cutting stroke.

The operation of our hydraulic operating mechanism may be conveniently stopped by manually moving the reversing valve V to its middle or 65 neutral position, which causes the piston 41 to move to the middle or neutral position shown in Fig. 6, in which it will be seen that the pressures are balanced on the two sides of the piston 41 and that the pipes 88 and 89 are both closed by 70 the piston 41. After being moved to this position, the piston 41 will remain indefinitely in neutral position, as any movement of the piston in either direction would partially uncover one of the pipes 88 or 89, thus reducing the pressure 75

on the side from which movement had occurred, so that a reverse or return movement to neutral position would immediately take place. Consequently the planer or other machine tool can be 5 manually stopped in any position by moving the reversing valve V to mid-position, and will remain at rest until the valve V is manually moved to one or the other of its operating positions.

Having thus described our invention and the 10 advantages thereof, we do not wish to be limited to the details herein disclosed, otherwise than as set forth in the claims, but what we claim is:—

1. Hydraulic actuating mechanism for a member connected to be reciprocated by relative movement of a cylinder and piston, said mechanism comprising a reversible discharge pump having two flow openings, means to continuously connect one opening to one end of said cylinder, means to connect the other opening to the other end of said cylinder, and means to effect discharge of said pump through one of said flow openings to cause travel of said reciprocated member in one direction and through the other flow opening to cause travel of said reciprocated member in the other direction, said latter means being controlled by said reciprocated member as it approaches a limit of travel and comprising pump-reversing mechanism, a cylinder and piston connected to move said mechanism, and a plurality of separate devices acting successively and automatically to determine different rates of movement of said latter piston in different portions of its stroke during a single pump reversal.

2. Hydraulic actuating mechanism for a member connected to be reciprocated by relative movement of a cylinder and piston, said mechanism comprising a reversible discharge pump having two flow openings, means to continuously connect one opening to one end of said cylinder, means to connect the other opening to the other end of said cylinder, means to effect discharge of said pump through one of said flow openings to cause travel of said reciprocated member in one direction and through the other flow opening to cause travel of said reciprocated member in the other direction, said latter means being controlled by said reciprocated member as it approaches a limit of travel and including devices effective to vary and control the rate of deceleration and the rate of acceleration of said reciprocated member during a single reversal thereof and to control each rate of change independent of the other rate.

3. Hydraulic actuating mechanism for a re-

ciprocated member comprising a variable delivery reversible discharge pump and devices controlled from said member for varying and reversing the discharge of said pump, said devices including a control cylinder and piston connected to reverse said pump, and means by which the relative rates of movement of said control piston in different parts of its stroke may be separately varied and controlled during said pump reversal.

4. Hydraulic actuating mechanism for a reciprocated member comprising a variable delivery reversible discharge pump, and devices controlled from said member for varying and reversing the discharge of said pump, said devices including a control cylinder and piston connected to reverse said pump and means to variably control the rate of movement of said control piston in different parts of its stroke and by which a predetermined dwell at the middle 10 portion of the stroke may be effected during said pump reversal.

5. Hydraulic actuating mechanism for a reciprocated member provided with a cylinder and piston, one of which is connected to said member, said mechanism comprising a variable delivery reversible discharge pump having discharge openings one of which is continuously connected to one end of said cylinder and speed control valve mechanism through which the other of said 20 discharge openings is connected to the opposite end of said cylinder, means controlled from said reciprocated member and effective to reverse the direction of discharge of said pump at each limit of travel of said reciprocated member, and means 30 to separately control the rate of deceleration and the rate of acceleration of said reciprocated member during a single pump reversal, whereby either rate of change may be independently varied during said single reversal.

6. Hydraulic actuating mechanism for a member connected to be reciprocated by relative movement of a cylinder and piston, said mechanism comprising a reversible discharge pump, means to reverse the direction of discharge of said pump, a storage for excess liquid, a by-pass connection from one end of said cylinder to said storage, and automatic means comprising a pressure operated valve, said latter means being effective to open said by-pass connection at one 40 limit of travel of said piston and when the pump is substantially in zero discharge position.
